DEVICE FOR APPLYING PAPER BAGS TO HANGER-SUPPORTED GARMENTS

Richard A. Keefe, Oak Park, Ill.

Application June 23, 1954, Serial No. 438,674

5 Claims. (Cl. 225—18)

The present invention relates generally to devices for applying to hanger-supported garments, paper bags having open bottoms and closed top portions with centrally disposed apertures therein for receiving the hooks of the hangers. More particularly, the invention relates to that type of device which is primarily designed for use in a dry cleaning establishment, comprises a vertical rod, a hook on the upper end of the rod for suspending the rod from a point a small distance beneath the ceiling of the establishment, a depending eye on the lower end of the rod for receiving the hook of a hanger with a cleaned garment thereon, a combined supporting and cutting member on the upper portion of the rod and a plurality of nested paper bags in surrounding relation with the rod and with the aperture defining parts of their closed top portions resting on the member, and is used, by first hooking the hook of the hanger onto the eye in order to suspend the hanger with the garment thereon from the lower end of the rod, then jerking or pulling downwards on the innermost bag in order to release it from the combined supporting and cutting member by causing the latter partially to rupture the aperture defining part of the closed top portion of the innermost bag, and finally sliding downwards the released innermost bag until it encases the garment on the suspended hanger and the closed top portion thereof rests on the shoulders of the garment.

In connection with a device of the aforementioned type, it has heretofore been proposed to cause or make the bags nest properly by either forming the bags so that they taper upwards and have non-parallel side margins or forming the bags so that they are generally rectangular but progressively increase in size from the innermost bag to the outermost bag. In practice, it has been found that the bags if formed so that they taper upwards for nesting purposes, are difficult to produce, result in wastage of paper and do not snugly and properly encase the hanger-supported garments to which they are applied. It has also been found that the bags if made rectangular but of progressively increasing size from the innermost bag to the outermost bag are difficult and costly to produce and nest.

The primary object of this invention is to provide a device of the type under consideration which is an improvement upon, and obviates the objections to, previously designed devices and is characterized by the fact that the paper bags are generally rectangular and the same in size and are maintained in nested relation due to a particular folding of their side portions whereby they are upwardly tapered when in nested relation and supported on the combined supporting and cutting member on the upper portion of the rod. Generally speaking, each bag is folded on straight upwardly convergent lines which extend upwards from the lower corners of the bag to the ends of the centrally disposed aperture in the closed top portion of the bag and result in the upper corner portions of the bag being in the form of in-folded triangular flaps which give the bag as a whole

2

an upwardly tapered configuration or contour. When the bag in connection with use of the device is slid downwards after the aperture defining part of its closed top portion is released by being ruptured or severed by the combined supporting and cutting member of the device, the flaps automatically swing outwards as the bag is slid downwards over the garment on the eye-suspended hanger.

Another object of the invention is to provide a device of the last mentioned character in which the triangular flaps at one side of the nested bags are folded forwards and the triangular flaps at the other side of the nested bags are folded rearwards.

A further object of the invention is to provide a device of the type and character under consideration in which the combined supporting and cutting member is of novel construction and is so designed that it may be readily adjusted upwards on the rod when the nested bags are of large size and downwards on the rod when the nested bags are of intermediate or small size.

A still further object of the invention is to provide a bag applying device which is generally of new and improved construction, effectively and efficiently fulfills its intended purpose and is capable of being manipulated with facility and produced at a comparatively low cost.

Other objects of the invention and various advantages and characteristics of the present bag applying device will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a front view showing a bag applying device embodying the invention with a garment carrying hanger in suspended relation with the eye on the lower end of the vertically extending rod and before the innermost paper bag has been jerked or pulled downwards so as to release it from the combined supporting and cutting member on the upper portion of the rod.

Figure 2 is a similar view except that it shows the innermost bag after it has been jerked or pulled downwards so as to release it from the combined supporting and connecting member by causing the latter to rupture or sever the aperture defining part of the closed top portion of the innermost bag;

Figure 3 is a vertical section showing the innermost bag after it has been slid fully downwards so as to encase the garment on the eye-suspended hanger;

Figure 4 is a front view illustrating in detail the nested relation of the paper bags;

Figure 5 is a horizontal section taken on the line 5—5 of Figure 4 and showing the folded flap arrangement of one of the bags;

Figure 6 is a fragmentary perspective illustrating the manner in which the flaps of the down pulled innermost bag automatically open when the bag is brought into encasing relation with the garment on the eye-suspended hanger;

Figure 7 is an enlarged view, partially in section and partially in elevation, of the upper portion of the device;

Figure 8 is a horizontal section taken on the line 8—8 of Figure 7;

Figure 9 is a similar horizontal section except that it shows the combined supporting and cutting member turned 90° so as to release it for downward adjustment or sliding movement relatively to the vertically extending rod; and

Figure 10 is a perspective of the combined supporting and cutting member.

The device that is shown in the drawings constitutes the preferred form or embodiment of the invention. It is adapted for use in a dry cleaning or like establishment and serves as a medium or instrumentality for applying a paper bag to a cleaned garment 11 on a conventional hanger 12. The hanger is shown in the drawing as being of standard or conventional design and comprising a triangular wire body 13 with an upstanding hook 14 at its upper corner. As its principal components or parts, the device comprises a rod 15, a hook 16, an eye 17, a combined supporting and cutting member 18 and a plurality of nested paper bags 19.

The rod 15 when in its operative position extends vertically and is suspended by the hook 16 from a point a small distance beneath the ceiling of the establishment in which the device is employed. It is formed of wood or any other suitable material and is of such length that when it is in its operative position, its lower end is positioned at substantially shoulder height with respect to the floor of the establishment. The upper portion of the rod 15 is provided with an upper pair of outwardly extending lugs 20, an intermediate pair of outwardly extending lugs 21 and a lower pair of outwardly extending lugs 22. These pairs of lugs permit the combined supporting and cutting member 18 to be supported at different heights depending upon whether the paper bags are of large, intermediate or small size. The lugs 20 are positioned diametrically opposite one another and are located a small distance beneath the upper extremity of the rod. The lugs 21 are positioned diametrically opposite one another and are disposed in vertical alignment with, and a small distance beneath, the lugs 20. The lugs 22 are positioned diametrically opposite one another and are disposed in vertical alignment with, and a small distance beneath, the lugs 21.

The hook 16 of the device is suitably connected to, and projects upwards from, the upper extremity of the rod 15 and serves to suspend the rod from a horizontal bar 23. It is contemplated that the latter will be suitably supported so that it is disposed a small distance beneath the ceiling of the establishment where the device is employed. When it is desired to use the device, the hook 16 is hooked onto the horizontal bar 23 in order to hold the rod in a suspended position. It is contemplated that the rod will be removed from the bar 23 when the device is not being used or it is necessary to place another plurality of nested paper bags on the rod.

The eye 17 depends from the lower end of the rod 15 and embodies an upstanding screw threaded shank 24 which is screwed into the lower extremity of the rod. As shown in Figures 1, 2 and 3 of the drawings, the eye 17 is adapted to receive the hook 14 of the hanger 12 in connection with use of the device.

The combined supporting and cutting member 18 of the device is shown in the drawings as being supported on the upper lugs 20. It comprises a sleeve 25 and a pair of outwardly extending diametrically opposite triangular blades 26. The sleeve 25 of the combined supporting and cutting member is formed of sheet metal or other suitable material and extends around, and fits slidably on, the upper portion of the rod 15. The front and rear portions of the sleeve are struck or deflected outwards so as to form inwardly facing open ended vertically extending channels 27 which are of such cross sectional shape as slidably to receive the outwardly extending lugs when the combined supporting and cutting member is turned 90° from its normal position wherein the channels as shown in Figures 7 and 8 are out of vertical alignment with the lugs into the position shown in Figure 9 wherein the channels are in registry with the lugs and permit the combined supporting and cutting member to be slid upwards or downwards relatively to the rod. When the member is supported on the lugs 20

as shown in Figures 1, 2, 3 and 7 of the drawings and it is desired to lower the member so as to adapt the device for use with intermediate sized bags, the member is given a quarter turn so as to bring the channels 27 into registry with the lugs 20. The member is then slid downwards until the lower end of the sleeve 25 is positioned directly above the lugs 21. Thereafter the member is given another quarter turn in order to bring the channels out of alignment with the lugs 21 and cause the member 10 to be supported by such lugs. The same procedure is followed when it is desired to slide the member 18 downwards onto the lugs 22 so as to adapt the device for use with small sized bags. The blades 26 of the combined supporting and cutting member are welded or otherwise 15 fixedly secured to diametrically opposite portions of the sleeve 25 and are arranged so that they extend at right angles to the channels 27. The outer side edges of the blades are upwardly convergent. In addition, they are beveled so as to form cutting edges 28.

The paper bags 19 are generally rectangular in configuration and consist of front pieces 29 and rear pieces 30. They are adapted when in nested relation to surround the rod 15 and be releasably supported by the combined supporting and cutting member 18. The bottoms of the bags are open. The side margins of the front and back pieces of the bags are joined together and extend in parallel relation. The top margins of the front and back pieces 29 and 30 of the bags 19 are upwardly tapered so as to conform to the configuration of 25 the upper portion of the body 13 of the hanger 12. They are joined together except at the central portions thereof in order that the bags have closed upper portions with centrally disposed hook-receiving apertures 31 therein. In order to permit the bags to be nested closely together, 30 each bag is folded on straight upwardly convergent lines which extend upwards from the lower corners of the bag to the ends of the centrally disposed aperture in the closed top portion of the bag and result in the upper corner portions of the bag being in the form of in-folded 35 triangular flaps 32 which give the bag as a whole an upwardly tapered configuration or contour. As shown in the drawings, the in-folded triangular flaps at one side of the bags are folded forward and the flaps at the other side of the bags are folded rearwards. Each bag, with 40 the exception of the outermost bag, fits entirely within 45 the next outer bag. When the nested bags 19 are in their operative position, the aperture defining parts of the closed upper portions of the bags rest on the blades 26 of the combined supporting and cutting member 18.

The nested bags are mounted in place by inserting the rod 15 into the open bottom of the innermost bag and then shifting or sliding the rod upwards until the blades of the combined supporting and cutting member are in underlying relation with the aperture defining parts of the closed 50 upper portions of the bags.

When it is desired to use the device, the hook 14 of the hanger 12 is manipulated into hooked relation with the eye 17 in order that the hanger with the cleaned garment 11 thereon is suspended from the lower end of the 55 rod 15. Thereafter, the inner most bag is jerked or pulled sharply downwards in order to release it from its supported position with respect to the combined supporting and cutting member 18. In connection with the downward jerking or pulling action, the edges 28 of the blades 60 26 rupture or sever the aperture defining part of the closed upper portion of the innermost bag and thus release the bag. After release of the innermost bag from the member 18, the bag is slid downwards into a position 65 wherein it encases the garment 11 and its closed upper portion rests on the shoulders of the garment. In connection with downward sliding movement of the innermost bag, the infolded triangular flaps 32 automatically swing outwards into an open position when the fold lines thereof encounter or engage the shoulders of the garment. After 70 75 the innermost bag is slid downwards so as to encase the

hanger-supported garment, the hanger is removed from the rod 15 by detaching the hook 14 from the eye 17. It is contemplated that the heretofore mentioned operations will be repeatedly carried out until all of the bags 19 have been used. Thereafter, a new group of bags is applied to the rod so that the device is again in readiness for use.

The herein-described device is simple in design, effectively and efficiently fulfills its intended purpose and may be produced at a comparatively low cost due to the particular folded arrangement of the nested bags 19 and the construction or design of the combined supporting and cutting member 18.

The invention is not to be understood as restricted to the details set forth since these may be modified within the scope of the appended claims without departing from the spirit and scope of the invention.

Having thus described the invention what I claim as new and desire to secure by Letters Patent is:

1. As a new article of manufacture, a device adapted to be used in a dry cleaning or like establishment to apply bags to garments or other articles on conventional hook-equipped hangers and comprising a vertically extending rod provided at its upper end with means for suspending it from a support near the ceiling of the establishment and having at its lower end means whereby the hook of a hanger with a garment thereon may be detachably connected to it, a combined supporting and cutting member mounted on the upper portion of the rod, and a plurality of generally rectangular uniformly sized nested bags having open bottoms, substantially parallel side margins and closed top portions with centrally disposed hook-receiving apertures therein, extending around the rod, having the aperture defining parts of their closed upper portions resting normally on the combined supporting and cutting member and folded inwards on straight upwardly convergent lines which extend upwards from the lower corners of the bags to the ends of the centrally disposed apertures in the closed top portions of the bags and result in the upper corner portions of the bags being in the form of infolded triangular flaps which give the bags as a whole an upwardly tapered configuration and make for close nesting of the bags, the innermost bag being adapted, when a hanger with a garment thereon is connected to said means on the lower end of the rod, first to be jerked or pulled downwards in order to release it from the combined supporting and cutting member by causing the latter partially to rupture or sever the aperture defining part of the closed top portion of the innermost bag and then slid downwards into encasing relation with the garment on the connected hanger, said innermost bag being further adapted when slid into encasing relation with the garment on said connected hanger to have its flaps automatically swung outwards into an open position when the fold lines are brought into contacting relation with the portions of the garment that are on the ends of said connected hanger.

2. As a new article of manufacture, a device adapted to be used in a dry cleaning or like establishment to apply bags to garments or other articles on conventional hook-equipped hangers and comprising a vertically extending rod provided at its upper end with means for suspending it from a support near the ceiling of the establishment and having at its lower end means whereby the hook of a hanger with a garment thereon may be detachably connected to it, a combined supporting and cutting member mounted on the upper portion of the rod, and a plurality of generally rectangular uniformly sized nested paper bags having open bottoms, substantially parallel side margins and closed top portions with centrally disposed hook-receiving apertures therein, extending around the rod, having the aperture defining parts of their closed upper portions resting normally on the combined supporting and cutting member, and folded inwards on straight upwardly convergent lines which extend upwards from the lower corners of the bags to the ends of the centrally disposed

apertures in the closed top portions of the bags and result in the upper corner portions of the bags being in the form of infolded triangular flaps which give the bags as a whole an upwardly tapered configuration and make for close nesting of the bags, the flaps at one side of the bags being folded forwards and inwards and the flaps at the other side of the bags being folded rearwards and inwards, the innermost bag being adapted, when a hanger with a garment thereon is connected to said means on the lower end of the rod, first to be jerked or pulled downwards in order to release it from the combined supporting and cutting member by causing the latter partially to rupture or sever the aperture defining part of the closed top portion of the innermost bag and then slid downwards into encasing relation with the garment on the connected hanger, said innermost bag being further adapted when slid into encasing relation with the garment on said connected hanger to have its flaps automatically swing outwards into an open position when the fold lines are brought into contacting relation with the portions of the garment that are on the ends of said connected hanger.

3. A plurality of generally rectangular uniformly sized nested bags adapted to surround a vertically extending rod and to be temporarily suspended on a combined supporting and cutting member on the upper portion of the rod, further adapted to be slid downwards one at a time into encasing relation with garments or like articles on conventional hook-equipped hangers, having open bottoms, substantially parallel side margins and closed top portions with centrally disposed hook-receiving apertures therein, and folded inwards on straight upwardly convergent lines which extend upwards from the lower corners of the bags to the ends of the centrally disposed apertures in the closed top portions of the bags and result in the upper corner portions of the bags being in the form of infolded triangular flaps which give the bags as a whole an upwardly tapered configuration and make for close nesting of the bags.

4. A plurality of generally rectangular uniformly sized nested paper bags adapted to surround a vertically extending rod and to be temporarily suspended on a combined supporting and cutting member on the upper portion of the rod, further adapted to be slid downwards one at a time into encasing relation with garments or like articles on conventional hook-equipped hangers, having open bottoms, substantially parallel side margins and closed top portions with centrally disposed hook-receiving apertures therein, and folded inwards on straight upwardly convergent lines which extend upwards from the lower corners of the bags to the ends of the centrally disposed apertures in the closed top portions of the bags and result in the upper corner portions of the bags being in the form of infolded triangular flaps which give the bags as a whole an upwardly tapered configuration and make for close nesting of the bags, the flaps at one side of the bags being folded forwards and inwards and the flaps at the other side of the bags being folded rearwards and inwards.

5. As a new article of manufacture, a device adapted to be used in a dry cleaning or like establishment to apply bags to garments or other articles on conventional hook-equipped hangers and comprising a vertically extending rod provided at its upper end with means for suspending it from a support near the ceiling of the establishment and having at its lower end means whereby the hook of a hanger with a garment thereon may be detachably connected to it, a combined supporting and cutting member located at the upper portion of the rod, adapted temporarily to support a plurality of nested bags with open bottoms and closed top portions with centrally disposed hook-receiving apertures therein, and consisting of a sleeve extending around, and slidably lengthwise of, said upper portion of the rod and oppositely disposed blades connected to, and projecting outwards from, the sleeve, and means adapted to support the combined sup-

porting and cutting members at different elevations on the upper portion of the rod and consisting of a vertical series of spaced apart outwardly extending lugs on said upper portion of the rod, the sleeve of the combined supporting and cutting member being adapted selectively to rest on any of the lugs and having in one portion thereof an inwardly facing vertically extending open ended channel adapted when the member is rotated so

that the channel is in registry with the lugs to permit the member to slide lengthwise of the rod into a position where it is disposed over any of the lugs and may be supported on the subjacent lug by turning it so as to move 5 the channel out of registry with the subjacent lug.
